(57) **CLAIM**

The ornamental design for a dental scan body as shown and described.

DESCRIPTION

FIG. 1 is a bottom perspective view of a dental scan body according to the present invention.

FIG. 2 is a top perspective view of the dental scan body of FIG. 1.

FIG. 3 is a front view of the dental scan body of FIG. 1; the rear view, left view and right view are each a mirror image of the front view.

FIG. 4 is a top view of the dental scan body of FIG. 1; and, FIG. 5 is a bottom view of the dental scan body of FIG. 1. In the drawings, the broken lines depict portions of the dental scan body that form no part of the claimed design.

1 Claim, 2 Drawing Sheets
